Inventor

JESSE B HARRIS

By C. P. Enochs

Attorney

UNITED STATES PATENT OFFICE.

JESSE B. HARRIS, OF MINNEAPOLIS, MINNESOTA.

REGULATOR.

Application filed February 18, 1925. Serial No. 10,031.

To all whom it may concern:

Be it known that I, JESSE B. HARRIS, a citizen of the United States, and a resident of Minneapolis, in the county of Hennepin and State of Minnesota, have invented new and useful Improvements in a Regulator, of which the following is a specification.

The main object of my invention is to provide a regulator wherein a thermostatic control device will mechanically and directly control an electrical circuit switch.

Another object is to provide an improved unit regulator that is self-contained.

Another object is to provide with a regulating device, lever and link mechanism that will automatically control an electrical switch.

With these and incidental objects in view, the invention consists of certain novel features of construction and combination of parts, the essential elements of which are hereinafter described with reference to the drawing which accompanies and forms a part of the specification.

25 In the drawing, Figure 1 is a side elevation, partly in section showing my improved regulator as it would be connected to a boiler and Figure 2 is a plan view of the same.

30 While I have shown my regulator in an embodiment whereby its action is determined directly by the temperature of the boiler to which the device is applied, the same principle works equally well where di-

35 rect pressure is applied to the actuating part of the mechanism such as in steam plants in which case the action is performed by the pressure of the steam, but as this pressure is directly proportional to the tem-
40 perature, the control is actually determined by the temperature of the boiler to which the regulator is applied.

45 As shown in the drawing, the base 1, which may be a casting or formed structure, has mounted thereon by screws 2, a thermostatic control element 3, which is preferably of the ordinary bellows type such as are commonly known, and as this part of the apparatus does not pertain to my invention, the details thereof will not be described except to state that the position of the pin 4 is determined by the temperature of the tube 5, which is inserted in the boiler 6, to which the device is applied.

55 As shown in Figure 1, the tube 5 is exteriorly threaded at 7 to engage with the

interior threads of the sleeve 8 and this sleeve is exteriorly threaded at 9 to engage with the interior threads 10 in the aperture of the boiler where the device is mounted.

60 At the opposite end of the frame 1, a conductel 11 is mounted by screws 12 and in this conductel is any ordinary type switch which has either a lever 13 extending therefrom, or has its individual lever, not shown, 65 rigidly fastened to the lever 13.

Hinged to the lever 13 at 14 is a link 15, which is threaded into the rod end 16 at its exteriorly threaded end 17.

70 The rod end 16 is hinged at 18 to the lever 19 and this lever 19 is carried by saddle 20 and the set screw 21 allows the lateral adjustment of the lever 19 with respect to the saddle.

75 The saddle 20 is hinged at 22 to the element 3 and rests on the pin 4, adjustable weights 23 and 24 being provided for varying the gravity pressure of the saddle 20 on the pin 4.

80 It is evident that if the switch in the conductel 11 is closed in the position shown in Figure 1, the upward movement of the pin 4 caused by increase in temperature in the boiler, will at a pre-determined point, open the switch thru the mechanism of the link 15 and the lever 13 and that conversely the lowering of the temperature in the boiler will by the retraction of the pin 4 allow the overbalancing weight 23 to close the switch.

90 The switch can of course be used to close any electrical circuit so the device can be used in controlling any kind of electrical device such as the circuit of an oil burner to which my regulator is peculiarly adapted.

95 While I have described my invention and illustrated it in one particular construction, I do not wish it understood that I limit myself to this particular embodiment, as it is evident that the application of the invention may be varied in many ways within the scope of the following claims:

Claims:

1. In a regulator, the combination with a base of a thermostatically operated element 105 mounted on said base and including a movable pin, a lever mounted on said element and in hinged relation thereto, an adjustable weight element on said lever, an electrical switch mechanism mounted on said base and link mechanism interposed between said switch mechanism and said lever,

whereby the movement of said pin will actuate said switch.

2. In a regulator, the combination with a base of a thermostatically operated element, including a movable pin, a nipple associated with said base and element and exteriorly threaded, a longitudinally adjustable lever mounted in hinged relation to said element, a longitudinally adjustable weight carried by said lever, a switch mechanism mounted on said base, a lever extending from said switch mechanism to actuate the same and a link hinged at one end to said last named lever and at the other end to said longitudinally adjustable lever whereby the movement of the said longitudinally adjustable lever will actuate said switch, the position of said pin determining the angular position of said longitudinally adjustable lever

3. In a regulator, the combination with a base of a thermostatic element mounted on said base, said element including a movable pin whose position is determined by the temperature to which said element is subjected, a saddle hinged to said element and having its free end resting on said pin, a lever mounted in said saddle and longitudinally adjustable therein, a pair of adjustable weights on said lever, each longitudinally adjustable along said lever, a switch mechanism mounted on the other end of said base and having a lever controlling said mechanism extending therefrom, a link hinged to said last named lever at one end and having a rod end threaded to its opposite end, said rod end being hinged to the free end of said first named lever.

JESSE B. HARRIS.
